(57) CLAIM

The ornamental design for a head wrap, as shown and described.

DESCRIPTION

FIG. 1 is a top front perspective view of a head wrap showing my new design;

FIG. 2 is a front elevation view thereof, with the rear elevation view being a mirror image thereof;

FIG. 3 is a right elevation view thereof, with the left elevation view being a mirror image thereof;

FIG. 4 is a top plan view thereof; and,

FIG. 5 is a bottom plan view thereof.

The cross-hatch shading is fragmentarily shown for convenience of illustration; it being understood that the cross-hatch shading is uniformly continued over the surface on which it appears.
